UNITED STATES PATENT OFFICE.

WILLIAM J. BURGESS, OF OLEUM, CALIFORNIA.

TOOL FOR TRUING CYLINDRICAL OBJECTS.

1,146,305.

Specification of Letters Patent. Patented July 13, 1915.

Application filed September 26, 1914. Serial No. 863,702.

To all whom it may concern:

Be it known that I, WILLIAM J. BURGESS, a citizen of the Dominion of Canada, residing at Oleum, in the county of Contra Costa, 5 and State of California, have invented new and useful Improvements in Tools for Truing Cylindrical Objects, of which the following is a specification.

This invention relates to tools for truing 10 cylindrical objects, such as crank-pins, journal-pins, wrist-pins and the like, the object being to provide a simple and effective tool which may be readily adjusted to any cylindrical object and which will enable variations to be readily observed therein and corrected 15 by means of an adjustable cutter bar which is carried by and forms a part of the tool, novel and efficient means being provided for adjusting the cutter bar and keeping 20 the cutting edge in true parallelism with the longitudinal axis of the cylindrical object being acted upon.

With the above and other objects in view, 25 the invention consists in the novel construction, combination and arrangement of parts, as herein described, illustrated and claimed.

In the accompanying drawings:—Figure 30 1 is a plan view of the tool of this invention; Fig. 2 is an end elevation of the same; Fig. 3 is a longitudinal section, taken in line 35 with the cutter bar; Fig. 4 is a cross section, taken in line with the fastening means and one of the cutter bar studs; Fig. 5 is a detail perspective view of the two frame members; Fig. 6 is a similar view of the cutter 40 head; Fig. 7 is a plan view of the cutter head with the adjacent face plate removed, showing the adjusting nuts and interposed gear; and Fig. 8 is a detail perspective view of the cutter bar.

The tool for truing cylindrical objects, contemplated in this invention, comprises an open skeleton and substantially cylindrical frame designated generally at A and comprising 45 the two substantially semi-cylindrical sections designated generally at a and b. The section a comprises the semi-circular end bars 1 and the connecting longitudinal bar 2 which is provided with open ended 50 slots 3, the purpose of which will appear. The other frame section b comprises the substantially semi-circular end bars 4 and the connecting longitudinal bars 5 and 6, the longitudinal bar 5 being provided with open 55 ended slots 6 adapted to register with the slots 3 above referred to.

The two frame sections a and b are pivotally connected together at 8 so that they may be thrown open with respect to each other to permit the frame to be again closed 60 around the pin or other cylindrical object to be operated upon. The free ends of the frame sections a and b are fastened together by means of bolts 9, which are pivotally connected at 10 to the section b of the frame, 65 said bolts being movable into and out of the slots 3 and 6 above referred to and being held by nuts 11 shown as milled to facilitate the tightening and loosening of the same by hand. 70

12 designates a pair of rollers, which are journaled in the frame section B, the pintles 13 of said rollers being received in openings therefor in the end bars 4. These rollers are arranged in spaced relation to each other 75 and are also parallel to each other and to the longitudinal axis of the frame and operate against the work so as to sustain the tool in proper relation thereto.

The other frame section A carries a cutter 80 head 14 which is provided with a cavity 15, in which are received nuts 16 and 17 and an intermediate actuating gear wheel 18, the nuts 16 and 17 being provided with teeth 19 which mesh with the teeth of the interposed 85 gear 18 so that as said gear 18 is turned, the nuts 16 and 17 are simultaneously and equally revolved. The cutter head 14 is mounted in fixed relation to the frame section a being secured terminally to the end 90 bars 1 by means of fasteners 20, such as screws or their equivalent.

21 designates a cutter bar provided with a cutting edge 22, said bar extending in parallel relation to the axes of the rollers 12. 95 The cutter bar 21 is formed with sockets 23 to receive the ends of a pair of threaded studs 24, the ends of the studs being received in the sockets 23 in which they are held by set screws 25, thus enabling said 100 studs to be easily removed from the cutter bar. The floor of the cavity or recess 15 is formed with holes 26 to receive the threaded studs 24 and permit the threaded portions of said studs to be engaged by the 105 rotary nuts 16 and 17. The cutter head is also formed with a central hole 27 to receive the rounded lower end 28 of a rotary shaft 29, the central portion of which is squared to fit into a correspondingly shaped opening 30 in the gear 18. Above the squared portion 29 the shaft is provided with a 110

rounded bearing portion 31 which is received in a central opening 32 in the face plate 33, which is secured by fasteners 34 of any suitable description to the outer face of 5 the cutter head 14. The shaft 29 finally terminates in a squared end portion 35 which is received in a squared socket or bore of a cap nut 36 having a polygonal face 39 adapted to receive a wrench whereby said 10 cap and the shaft 29 may be turned for revolving the gear wheel 18 and simultaneously turning the nuts 16 and 17 to advance or retract the cutter bar 21.

38 designates housing tubes extending outwardly from the face plate 33 to inclose the studs 24 and admit of the necessary longitudinal movement of the latter.

The inner face of the cutter head 14 is cut away as shown at 39 to form a seat for 20 a cutter bar 21 and the end bars 1 of the frame section A are likewise cut away at 40 to register with the cutaway-portion 39 of the cutter head for a like purpose.

In order to facilitate the turning of the 25 tool around the work which is ordinarily held stationary, a plurality of handles 41 are provided having forks 42, which are terminally secured at 43 to the end bars 1 and 4 of the frame members *a* and *b*. The 30 operator by grasping one after the other of the handles 41 may revolve or turn around the work or object being treated until said object is brought to a true cylindrical surface. The device will be found particularly 35 valuable in truing up by hand crank pins,

journals, wrist pins and similar bearing parts of engines and all kinds of machinery.

While the device is particularly useful on vessels at sea or at any points remote from repair places, said device will also be found 40 extremely useful in machine shops generally.

It will, of course, be understood that the device may be manufactured in various sizes to accommodate cylindrical objects of varying diameters and lengths. These and other 45 changes in the form, proportion and minor details of construction may be resorted to without departing from the principle or sacrificing any of the advantages of the invention.

I claim:—

In a tool of the class specified, a frame embodying a pair of semi-cylindrical sections separably connected together, parallel work-supporting rollers journaled in said frame 55 in spaced relation to each other, a cutter head carried by and bearing a fixed relation to one frame section, a cutter bar extending in a plane parallel to the longitudinal axes of said rollers, threaded studs on said cutter bar, adjusting nuts on said studs rotatable in relation to the cutter head, and means for simultaneously and equally rotating said nuts.

In testimony whereof I affix my signature 65 in presence of two witnesses.

WILLIAM J. BURGESS.
